UNITED STATES PATENT OFFICE.

EDWIN J. YOUNG, OF WADSWORTH, OHIO, ASSIGNOR TO THE OHIO
INJECTOR COMPANY, OF SAME PLACE.

INJECTOR.

SPECIFICATION forming part of Letters Patent No. 628,684, dated July 11, 1899.

Application filed January 16, 1899. Serial No. 702,255. (Model.)

To all whom it may concern:

Be it known that I, EDWIN J. YOUNG, a citizen of the United States, residing at Wadsworth, in the county of Medina and State of Ohio, have invented a certain new and useful Improvement in Injectors, of which the following is a full, clear, and exact description.

This invention relates more especially to that class of injectors which are used on locomotives; and the object of the invention is to provide for the delivery of the water to the boiler when quite warm or hot and also to enable the engineer constantly to observe the operation of the injector at the overflow.

15 In carrying out my invention I use a main overflow-valve located just over the overflow-nozzle and operated positively by connection with the steam-valve-actuating devices, so that the said main overflow-valve is always open in starting or stopping the injector and when the steam is shut off from the injector and is closed gradually as the steam is admitted to the injector, the said valve serving also to exhaust the steam for 25 raising the water. This main overflow-valve is not wholly closed until the jet is established, and when it is closed the steam-valve is wide open. In connection with this main overflow-valve I use an auxiliary or secondary 30 overflow-valve, which is opened when the injector is at work in order to enable the engineer to observe the spilling at the overflow, and thus have visible evidence of the operation of the injector. When extremely warm 35 water is used, both the main and the auxiliary overflow-valves are closed, so as to prevent the injector from spilling at the overflow.

Having thus stated the principle of my invention, I will proceed now to set forth the best mode in which I have contemplated applying that principle, and then will particularly point out and distinctly claim the part, improvement, or combination which I claim 45 as my invention.

In the accompanying drawings, illustrating my invention, in the several figures of which like parts are similarly designated, Figure 1 is a perspective view of a locomotive-injector constructed in accordance with my inven-

tion. Fig. 2 is a vertical longitudinal section of same. Fig. 3 is a vertical transverse section taken substantially in the plane of the center of the overflow. Fig. 4 is a partial end view taken substantially in the plane 55 immediately to the right, Fig. 2, of the water-valve handle. Fig. 5 shows the details of construction of the water-valve-operating device.

The casing *a* may be of approved form and 60 provided with the steam-inlet *b*, the water-inlet *c*, the overflow *d* and its passage *d'*, and the boiler-tube *e*.

f is a socket to receive the bolt by which the injector is applied to a locomotive. 65

The steam-valve *g*, reducing-nozzle *g'*, steam-jet *g''*, lifting-tube *g''*, combining-tubes *g''*, *g''*, delivery-tube *g''*, and check-valve *g''*, all arranged in alinement within the casing *a*, may be of any approved construction. 70 As herein shown, they are substantially similar in construction and operation to equivalent parts in my Patent No. 495,286, dated April 11, 1893, and as in that patent, so here, the steam-valve has the valve-rod *i*, 75 which is connected by a yoke *i'* with the handle-rod *i''*, the latter being pivoted upon the casing and having a vibratory motion thereon which is converted into a rectilinear reciprocating motion of the valve-stem. 80

The steam-valve is arranged in a cylinder *a'*, which is made as a screw-cap fitted in the end of the casing *a* and provided with a stuffing-box and gland *a''* for the valve-rod *i*.

j is the main overflow-valve, which is substantially a piston arranged in a segmental chamber *j'*, which is located crosswise of the overflow-passage *d'* and has the transverse valve-seat *j''* interposed between the overflow-chamber and the overflow, and this chamber 90 *j'* is accessible through a screw-cap *j''*. The valve *j* is provided with a valve-stem *l*, which passes through a tube or sleeve *m*. The tube or sleeve *m* is supported in the wall *m'* of the casing *a* and extends thence out beyond said wall and forms an inclosing bearing for said stem. Surrounding this sleeve *m* is a shell *n*, the inner end of which is enlarged and perforated, as shown at *n'*, to form the water-passage-controlling valve. This enlargement 100

n', which forms the water-valve, is properly seated to rotate in the water-tube *c* to permit the passage of the water into the injector and to cut off the supply. Said valve is removably seated in the casing by a stuffing-box *n*², tapped into the said casing and supplied with the gland *n*³ in order to make a tight joint. The outer end of the shell *n* extends beyond the sleeve *m* and is supplied with a suitable gland or stuffing-box *o*.

The stem *l* is connected by a yoke *l'* with the steam-valve rod *i* and derives reciprocating motion therefrom. The sleeve *m*, which forms a bearing for the valve rod or stem *l*, while permitting the free reciprocation of the said stem, is made steam-tight by terminating within the packed end of the shell *n*.

In order to operate the water-valve, its shell *n* is slabbed off, as shown at *n*⁴, Fig. 4, and such slabbed-off portion is provided with the ring *p*, Figs. 4 and 5, having its internal bore complementary to the external contour of the slabbed-off portion of the shell *n*, so as to turn with said shell. This ring *p* is provided with a lug *p'* to coöperate with the handle presently described, and it also has the stop-lugs *p*² *p*³, which come in contact with the casing to limit the movement of the water-valve. *q* is a handle having the ring end *q'*, which encircles the projecting end of the shell *n* next adjacent the ring *p*, and the ring end *q'* has a number of grooves *q*², with either one of which the lug *p'* of the ring *p* is engaged in order to set the handle *q* normally to the right or left hand or midway, according to the location of the injector and the engineer's preference. The gland or stuffing-box *o* may serve as the medium, with or without the nut *o'*, for holding the handle *q* in operative connection with the ring *p*, and when the handle and ring are connected as described then by vibration of the handle the water-valve may be rotated and more or less opened or closed, as may be desired.

The ring *p* may be provided with a scale *r* to coöperate with indexes *r'* on the casing, as in Fig. 4, in order to indicate the position of the water-valve.

The auxiliary overflow-valve *s* may be of the ordinary check-valve construction; but I prefer to supply it with the adjustable stem *s'*, which may be screwed down tight, so as to prevent the opening of the check-valve *s*, and consequently the automatic operation of said valve, this being a desirable feature with some engineers and in some circumstances.

It will be observed that the steam-inlet *b* is divided from the water-chamber by the wall *t*, and that the water-inlet tube and the water-chamber are separated by the valve *n'*, and that the water-chamber and the overflow-chamber are separated by the wall *m'*, and that the overflow-chamber and the overflow-nozzle are separated by the valve-seat *j*² and valve *j*.

It will be seen that the combining-tubes are erected in or form part of the skeleton or

open-work or perforated frame *g*⁹, so that the spilled water may escape into the overflow-chamber.

In ordinary injectors where the overflow is open the water becoming warm expands and escapes at the spills and goes out at the overflow, while by closing the overflow and holding the water under pressure it is possible with my injector to force the water to the boiler at a temperature some thirty or thirty-five degrees warmer than with the overflow open.

If the auxiliary overflow-valve be left open, my machine will work as an open-overflow machine and will show the spill at the nozzle or exhaust, and thus the engineer may know when the jet is broken. As this auxiliary overflow-valve is quite small, much less water will spill when the jet is broken than is the case with the ordinary injector. This auxiliary overflow-valve may be closed and retained closed so as to cause the machine to exhaust, as it will, freely through the main overflow-valve. This main overflow-valve *j* is always open in starting or stopping the injector and when the steam is shut off from the injector and is closed gradually as the steam is let into the injector, and as the injector exhausts through this valve the said valve practically controls the raising or lifting of the water. This valve is not wholly closed until the jet is fully established, and it is not closed until the steam-valve is wide open.

In starting the injector the auxiliary valve *s* is not necessarily used, as the main valve *j* has sufficient exhaust to start the injector. The auxiliary valve is only used as such when it is desired to watch the operation of the injector by means of spilling at the overflow.

It is possible to work the injector with the auxiliary valve kept closed, as already indicated, and some engineers so prefer, while others require that this valve be capable of being opened in order that they may see when the jet is broken by watching the spilling at the overflow.

When it is desired to work extremely warm water, both of the valves *j* and *s* must be closed to prevent spilling through the overflow.

I do not limit my invention to the mere details of construction and wish to be understood as so claiming my said invention.

What I claim is—

1. An injector, having a steam-valve, a main overflow-valve, a water-chamber, an overflow-chamber, and a tube or sleeve *m* which separates the said water-chamber from the overflow-chamber, the overflow-valve rod extending through said tube or sleeve and connected with the steam-valve-operating mechanism, substantially as described.

2. An injector, having a steam-valve, a main overflow-valve which controls communication between the combining-chamber and the overflow-chamber, connections between the two valves, and a tube or sleeve separating the

water-chamber from the overflow-chamber and through which the said overflow-valve rod passes, substantially as described.

3. In an injector, an overflow-valve having a stem extending longitudinally through its casing, a tubular bearing for said stem, a tubular water-valve surrounding the said bearing, and means to rotate the said water-valve around said bearing to open and close the waterway, substantially as described.

4. In an injector, an overflow-valve movable longitudinally of the machine, a longitudinal bearing for its stem, a water-valve made as a tube and surrounding said bearing, the outer end of the said tube provided with a handle for operating the same and capable of adjustment for use on the right-hand or the left-hand side or at intermediate points, substantially as described.

20 5. An injector, comprising a steam-valve, a main overflow-valve, connections between them by which they are operated simultaneously, and an auxiliary overflow-valve of relatively small size and adapted to be operated

independently of the main valve and the 25 steam-valve, substantially as described.

6. In an injector, the combination with a reciprocating longitudinally-arranged overflow-valve, and a bearing-sleeve therefor arranged transversely of the waterway, of a 30 water-valve made as a tube and supported upon the said bearing-sleeve and projecting outwardly of the casing, and means to operate it, substantially as described.

7. In an injector, a tubular water-valve having an externally-projecting slabbed-off end, a complementary ring applied to said slabbed-off end and constructed with a lug, and an operating-handle provided with grooves for adjustable connection with the lug of the said 35 ring, substantially as described.

In testimony whereof I have hereunto set my hand this 12th day of January, A. D. 1899.

EDWIN J. YOUNG.
